UNITED STATES PATENT OFFICE.

FRANCIS ILLÉS, OF BUDAPEST, AUSTRIA-HUNGARY.

BOTTLE-STOPPER.

SPECIFICATION forming part of Letters Patent No. 770,721, dated September 20, 1904.

Original application filed October 23, 1901, Serial No. 79,738. Divided and this application filed November 7, 1903. Serial No. 180,275. (No model.)

To all whom it may concern:

Be it known that I, FRANCIS ILLÉS, a subject of the Emperor of Austria-Hungary, residing at Budapest, Austria-Hungary, have 5 invented a certain new and useful Improved Bottle-Stopper, of which the following is a description.

The present invention relates to bottle-stoppers for bottles containing aerated or 10 other liquids under pressure; and it consists of the details of construction hereinafter set forth, and particularly pointed out in the claim.

In order to render the present specification 15 easily intelligible, reference is had to the accompanying drawings, in which similar letters of reference denote similar parts throughout both views.

Figure 1 is a part vertical section through 20 the stopper and upper part of the bottle, and Fig. 2 is a horizontal section on the line $\alpha\alpha$ of Fig. 1.

The stopper or bottle-closure g is provided 25 with a boring or opening a and is fitted into the bottle-neck f advantageously by means of a rubber or other packing ring q . The stopper is further provided with a lateral orifice c , into which a valve extends, consisting of a rubber or other sheath having the valve- 30 body b formed thereon and being mounted on or drawn over the arm d of a bell-crank lever $d\ h$. The sheath b is provided with a flange k , which fits over the lateral orifice and may be tightly secured in position by 35 means of a ring l , to which the bell-crank

lever is pivoted, extending round the stopper and being tightened up by means of a clamping-screw p .

A spring i is inserted between the handle or arm h and the stopper g , which spring has 40 the tendency to press the handle h outwardly, and thus to hold the head b of the valve tightly against the end of the orifice a and keep the bottle closed. When liquid is to be poured out, the handle h is simply pressed against or 45 toward the stopper, and the valve-head b thus forced away from the opening a , so that the liquid will flow out under pressure.

I claim as my invention—

In a bottle-closure, the combination of a 50 bell-crank lever having one arm extending approximately horizontally into the bottle-closure and carrying a valve of yielding material adapted to close the outlet-channel of the bottle-closure and having the other arm 55 located outside the bottle-closure and extending upwardly in proximity to the closure, a spring to normally hold the bell-crank in position to retain the said valve closed and a band around the bottle-closure to support the 60 bell-crank pivotally in the said bottle-closure, and means for rendering the joint to the interior of the bottle air-tight, substantially as described.

In witness whereof I have hereunto set my 65 hand in presence of two witnesses.

FRANCIS ILLÉS.
